UNITED STATES PATENT OFFICE

IRVING PHILLIPS, OF PHILADELPHIA, PENNSYLVANIA

FEED AND DELIVERY MECHANISM

Application filed June 29, 1925. Serial No. 40,337.

My invention provides feed and delivery mechanisms with means whereby one of such mechanisms controls the other to render the controlled mechanism ineffective should the controlling mechanism fail to perform its normal function. Such means may, however, be rendered inoperative when the failure of the controlling mechanism to perform its normal function results from a prior default 10 of the controlled mechanism.

My invention is particularly applicable to a printing press of the bed and platen type equipped with a so-called Miller feeder having a feed rack for inserting a sheet between 15 the bed and platen for printing, and delivery fingers for seizing and removing the printed sheet. In such mechanisms, the failure of the delivery fingers to remove a printed sheet results in the crumpling of such sheet by the 20 feed rack upon its next forward movement, with resultant jamming of the press, damage to the types and destruction of material. Even if an operative be in attendance and observe the failure of the delivery fingers, the 25 momentum of the fly wheel and heavy moving parts of the machine is such as to render impracticable the stoppage of the machine before serious damage is done.

By my improvements means are provided 30 whereby the failure of the delivery fingers to remove a printed sheet from between the platen and bed automatically cuts off the suction to the feed mechanism so that no sheet is delivered to the feed rack, renders the feed rack actuating mechanism inoperative, and trips the printing mechanism so that the platen and bed are not brought together. If, however, no sheet has been delivered by the feed 35 rack to the platen, so that there is no sheet 40 there for removal by the delivery fingers, the means which otherwise cuts off the suction, stops the feed rack and trips the press are rendered ineffective.

The characteristic features and advantages 45 of my improvements will more fully appear from the following description and the accompanying drawings illustrating a preferred embodiment thereof.

In the drawings, Fig. 1 is a side elevation of 50 apparatus embodying my invention showing

the feed rack advanced and the delivery fingers retracted; Fig. 1^a is an enlarged fragmentary view of a portion of the slide 50 and arm 21 showing the trigger block and guard as viewed from the right of Fig. 1^b; Fig. 1^b is a fragmentary view illustrating the slide and pivoted trigger block; Fig. 2 is a side elevation of the apparatus shown in Fig. 1 showing the delivery fingers advanced and the feed rack retracted; Fig. 2^a is a fragmentary view of the delivery fingers and probe in closed position; Fig. 2^b is a fragmentary view of the same parts with the delivery fingers and probe elevated; Fig. 2^c shows the same parts with the delivery fingers gripping a sheet and the probe supported thereby; Fig. 3 is a plan view of the apparatus with the delivery table broken away, taken in the direction indicated by the arrow in Fig. 2; Fig. 4 is a longitudinal sectional view taken 70 on the line 4—4 of Fig. 1; Fig. 5 is a transverse sectional view taken on the line 5—5 of Fig. 3; Fig. 6 is a transverse sectional view taken on the line 6—6 of Fig. 3; Fig. 7 is a transverse sectional view taken on the 75 line 7—7 of Fig. 3; Fig. 8 is a transverse sectional view on the line 8—8 of Fig. 3; Fig. 9 is an enlarged diagrammatic view of the control shaft and its associated parts; Fig. 10 is a face view of the feed rack actuating cam; Fig. 11 is a top plan view of the delivery fingers and their operating shafts on an enlarged scale, and in a slightly advanced position; and Fig. 12 is a slightly distorted perspective view showing the arm for oscillating the 85 delivery fingers and its connections in assembled relation.

As illustrated in the drawings, (Figs. 1, 2, 3 and 4) my improvements are applied to a printing press comprising a relatively oscillatory platen 1 and bed 1' having connected therewith a frame 2 which supports a stock table 3 and a delivery table 4. The sheets to be fed to the platen are picked up from the table 3 by the separator feet 5' of the bar 5 95 and positioned thereby in the path of the grippers 6 of the feed rack 7.

The side arms of the feed rack 7 have toothed surfaces 8 engaged by gear wheels 9 fixed on a shaft 10 journalled in and ex- 100

tending across the frame, but omitted from most of the figures of the drawings to avoid confusion this portion of the mechanism being well known to those skilled in the art. 5 One of the gear wheels has fixed thereto a pinion 11 meshing with the teeth of a quadrant 12 pivoted on the bearing 13 of the frame in the usual manner.

10 The quadrant is oscillated on its pivot, to reciprocate the feed rack 7, by the engagement of its roller 14 with the cam slot 15 in the disk 16 fixed on the driving shaft 17. An auxiliary slot 15' in the disk 16 permits the roller 14 to ride idly when the feed quadrant 15 12 is held up out of engagement with the pinion 11 as hereinafter described; a spring 12' tending to draw the quadrant 12 downward.

15 The opposite end of the shaft 17 has fixed thereto a disk 18 from which projects a crank pin 19 (Figs. 1, 2 and 12) which is engaged in the curved slot 20 of the delivery arm 21 having a shaft 22 journalled in the bearing 23 of the frame. A shaft 24, extending over 20 the table, has fixed to the respective ends thereof brackets 25 and 26, the former having its hub 26' journalled in a bearing 21a projecting laterally from the top of the lever 21, whereby the shaft 24 is rotatably supported.

25 The bracket 25 has a link 27 pivotally connected with an arm 25a thereof, the link having thereon a roller 27' operating in a cam slot 28', in a movable bracket 28 for suitably positioning the shaft to cause the delivery fingers to grasp a printed sheet on the platen. The bracket 28 is supported by a bracket 28a journalled on the projecting end of the shaft 22 and pivotally connected with the bracket 28. The member 28a may be slightly rocked 30 by a part of the press or feeder in the usual manner.

35 The shaft 24 has fixed thereto several pairs of delivery fingers 29 and each pair of delivery fingers has pivoted between them on a 40 pintle 40' a complementary delivery finger 30. The pivoted fingers 30 may be rocked upward from the fingers 29 by springs 31 but are normally tilted to form closed jaws by the engagement with the rears thereof of cams 50 32 carried on a shaft 33 journalled in arms 25b and 26b of the brackets 25 and 26. The shaft 33 has fixed on the end thereof an arm 34 connected by a link 35 with the lever 36 having the arms 37 and 38 adapted to be 55 rocked against the tension of a spring 33' by engagement with set screws 39 and 39' to permit the delivery jaws or fingers to be opened by the springs 31.

60 In accordance with my invention, a feeler lever 40 is pivoted on a pintle 40' on one or more of the pairs of fingers 29 and has on the forward end thereof a probe 41 which passes through the slot 42 in the end of the pivoted finger 30 to determine whether a sheet 65 is gripped between the fingers 29 and 30. The

probe 41 is normally pressed into the slot 42 by the action of a spring 43 fixed on the shaft 24 and engaging the tail of the lever 40. The movement of the feeler 41 downward into the slot 42 is limited by the engagement of the lever 40 with the stop or yoke 44 fixed on the fingers 29.

70 The lever 40 is rocked to lift the feeler 41 by the engagement with the tail 45 thereof of a trip or flange 46 on a shaft 47 journalled in arms 25c and 26c of the brackets 25 and 26 fixed to the shaft 24. (Figs. 2 and 12). The shaft 47 also has fixed thereto a flange 48 transverse to the trip or flange 46 and adapted to be engaged by the tail 45 of the feeler 40 75 when the latter is depressed. The movement of the shaft 47 is limited by the engagement of the flange 48 with the part 45, which, however, passes freely under the flange 48 when its forward end is held elevated by the engagement of the probe 41 with a sheet of paper between the fingers 29 and 30.

80 The shaft 47 has on the end thereof the crank arm 47' (Figs. 2 and 12) with which is connected a coiled spring 49 anchored to the lever arm 21. A slotted slide 50 is pivotally connected with the crank arm 47' and is reciprocable on the arm 21, to which it is connected by the stud 21'. A roller 51 on the bottom of the slide 50 rides over the member 28 and is engaged by the detachable cams or nose pieces 52, 52' the latter of which is preferably made adjustable. The engagement of the roller 51 with the nose pieces 52, 52', elevates the slide 50 against the action of the spring 49 and rocks the shaft 47 and flange 46, thereby tilting the feeler 40 and withdrawing the probe 41 from the slot 42. When the roller 51 is moved off of the nose pieces 52, 52', the spring 49 rocks the arm 47' and shaft 47 to depress the slide 50 unless prevented by the elevation of the tail 45 into the plane of the flange 48 when there is no sheet between the jaws 29, 30 to support the probe 41. From the foregoing it will be understood that when the roller 51 is at the base of the cam 52' the fingers 29 and 30 are closed and the probe depressed. As the roller rides to the top of the cam 52' the fingers are 100 opened and the probe is elevated by the engagement of the flange 46 with the tail 45.

105 The sheet entering between the fingers is gripped thereby upon the closure of the fingers as the roller 51 recedes to the base of the cam 52' and the probe is supported by the sheet so that the tail 45 clears the flange 48, which has been turned to engaging position. But should no sheet have been seized by the fingers, the probe is depressed and the tail 45 engages the flange 48.

110 A trigger block 52a is hinged by a pintle 52' to a bracket 50" on the slide 50 and is normally pressed toward the guard 53' by a spring 53. The block is so mounted as to 115

120 125 130

yield to pressure in one direction only and is protected by the guard and guide 53'.

The movement of the slide 50 moves the trigger or block 52a out of and into position for engaging and rocking a crank arm 54 on the end of a shaft 55 journalled in the frame and positioned by a spring 56. A crank arm 57 on the inner end of the shaft 55 has pivotally connected therewith a reciprocable slide 58 provided with a tooth 59, which is drawn forward by the rocking of the shaft 55 to rock the pivoted detent 60 (see Figs. 7 and 9) against the action of the spring 61 when the slide 58 is elevated as hereinafter described. The detent 60 contains an aperture or recess for the engagement of a pin or shoulder 62a on the main control shaft 62.

The shaft 62 is journalled in the frame and is constantly urged in a clockwise direction by the coiled spring 63. The control shaft 62 has fixed thereon a stop arm 62b, a yoke 62c, a cam 62d, and may be manually rotated counter to the action of the spring 63 by the link mechanism 62e operable by a push rod 64.

When the shaft 62 is manually turned by the push rod 64 anti-clockwise, the spring 63 is wound up and held under tension by the engagement of the pin 62a in the aperture in the detent 60 which is pressed by the spring 61 into position for holding the pin 62a. In this position of the shaft 62, its members 62b, 62c and 62d are inoperative.

When, however, the arm 54 is rocked by the engagement of the trigger 52a, it acts through the parts 55, 57, 58 and 59 to draw the detent 60 away from the pin 62a and release the shaft 62, which is immediately rotated by the spring 63.

The rotation of the shaft 62 by the spring 63 moves the arm 62b under the catch 65 of the quadrant 12 and thereby checks the movement of the feed rack 7; causes the yoke 62c to operate the stem 66 of the valve 67 which stops the exhaustion of air through the tubes 68 so that there is no longer suction on the feet 5' of the bar 5; and causes the cam 62d to operate the mechanism 69 connected with usual trip mechanism for tripping the bed and platen of the press.

The detent 60 is tripped by the tooth 59 only when the slide 58 is elevated by the arm 70 loosely pivoted on the shaft 71 journalled in the frame.

The shaft 71 has fixed thereto arms 72 normally elevated by a spring 73 but intermittently depressed by the engagement of a cam 74 on the main driving shaft 17 with a roller 75 on one of the arms 72. The forward slotted ends of the arms 72 engage and operate the slides 76 reciprocable in the guides 77 and supporting the bar 5.

A slotted lever 78 is pivotally mounted on the pin 79 fixed to the frame and is rocked by a pin 80 fixed to a lever arm 72 to elevate

or depress a link rod 81 passing through an apertured offset 82 on the bent arm 70 loosely journalled on the shaft 71. The movements of the rod 81 are transmitted to the arm 70 through coiled springs 84, 84' engaging opposite surfaces of the offset 82 and held under tension by the collars or stops 83.

When the sucker bar 5 is elevated by the arms 72 and spring 73, the lever 78 is elevated and acts through the spring 84 to elevate the arm 70 and lift the tooth 59 of the slide 58 into the plane of the detent 60. When, however, the arms 72 are depressed through the action thereon of the cam 74, the lever 78 acts through the spring 84' to elastically depress the arm 70, so that the tooth 59 drops below the plane of the detent 60.

A roller 85 is carried by the arm 70 and when the latter is depressed rides upon the periphery of the collar 86 fixed on the shaft 17, or enters the notch 86' thereof if the lever 70 is held depressed by the action of the spring 84' until the notch 86' is turned by the shaft 17 into registration with the roller. When the roller enters the notch it rides around the interior channel 87 of the collar until again brought into registration with the notch at a time when the lever 78 is elevated and applies pressure through the spring 84 to the arm 70 to eject the roller from the channel 87.

The shaft 17 has thereon a cam 17' for operating the valve stem 66 in synchronism with the operation of the arms 72 by the cam 74, so that when the bar 5 is depressed the openings in the separator feet 5' are connected through the ducts 68 with a duct 68a leading to a vacuum pump, not shown. The closing of the orifices of the middle separator foot by a sheet of paper permits the exhaustion of a chamber 90 through the duct 68b connecting such chamber and separator foot. The exhaustion of the chamber 90 elevates a weight 91 therein from the tail of a pivoted pawl 92 having a weighted head adapted to be tilted by the weight 91 into engagement with a notched rod 93 fixed on the bar 5 to prevent upward movement thereof.

Should the separator feet fail to pick up a sheet of paper from the table 3, the orifices in the middle separator foot 5' are not closed and the chamber 90 is not exhausted. Consequently the weight 91 tilts the head of the pawl 92 into engagement with the rod 93 and the bar 5 is held down after the cam 74 has passed the roller 75.

In the beginning of a normal cycle of operation of the machine, the bar 5 is in an elevated position above a stack of sheets on the stack table 3, the feed rack 7 is retracted, and the delivery fingers 29 and 30 have grasped and started to remove a sheet from the platen of the press. The push rod 64 is pushed in

and the shaft 62 is turned so that the parts 62b, 62c and 62d are inoperative and the spring 63 is under tension, the shaft being held in such position by the engagement of the detent 60 with the pin or shoulder 62a on the shaft 62.

The rotation of the main shaft 17 acts through the mechanism described to lower the bar 5 into engagement with the sheet stack and open the valve 66 for exhausting the feet 5'. If a sheet is picked up, the weight 91 is elevated by suction and the head of the dog 92 drops out of position for engaging the groove in the rod 93, so that the bar 5 may be elevated by the action of the spring 73 on the arm 72. The sheet lifted by the bar 5 is seized by the jaws 6 and delivered by the feed rack to the platen. If, however, the separator feet 5' should fail to pick up a sheet, the ports in the middle separator foot are left open and atmospheric air is admitted to the chamber 90 which causes the weight 91 to drop upon the tail of the dog 92 and tilts its nose into position for engaging in the notch in the bar 93 thereby holding the bar 5 in its depressed position until a further cycle of the machine when the separator feet pick up a sheet of material with resulting exhaustion of the air from the chamber 90 and the release of the detent 92 from the bar 93. So long as the bar 5 is held depressed by the detent 92 the roller 85 rides around in the channel 87, and the lever 70 is held down so that it cannot raise the tooth 59 on the lever 58 into the plane of the keeper 60, hence oscillation of the arm 54 does not stop the machine so long as the bar 5 is held down by the pawl 92.

When, in a further cycle of the machine, a sheet of paper is picked up by the separator feet 5', and suction is created in the chamber 90 to lift the weight 91 from the tail of the pawl, so that the head of the latter drops out of the path of the rod 93, the arm 72 acts through the lever 78, rod 81, collar 83 and spring 84 to press the roller 85 against the outer wall of the channel 87, so that when the slot 86' registers with the roller 85, after a half revolution of the shaft 17, the roller is ejected from the channel 87 and the lever 70 is elevated by the spring 84 to lift the tooth 59 on the link 58 into a plane for engagement with the detent 60.

The sheet delivered to the platen is printed by the form on the bed of the press, and as the platen and bed reopen the arm 21 moves forward (toward the left in Figs. 1 and 2). The engagement of the roller 51 with the cam 52' elevates the slide 50 to operate the crank arm 47' and turn the shaft 47 so as to tilt the forward flange 46 thereon into engagement with the tail 45 of the lever 40 and retract the feeler 41 from the aperture 42 in the jaw 30. When the arm 38 contacts with the stop 39', the pressure of the cams 32 on the ends

of the jaws 30 is released and these jaws are opened by the springs 31. As soon as the lever arm 21 starts backward, the cams 32 are tilted through the action of the spring 33' connected to arm on the shaft 33 to close the jaws 30 on the sheet which has been printed and lift it from the platen. When in the rearward movement of the arm 21 (toward the right in Figs. 1 and 2) the roller 51 has passed over the apex of the forward cam 52', the roller 51, slide 50, and connected mechanism tend to drop down under the urge of the spring 49 so that the trigger 52a will pass below the plane of the arm 54, provided that the feeler 41 is supported by a sheet of paper grasped between the jaws 29 and 30 so that the tail 45 clears the rearward flange 48 on the shaft 47. As the roller 51 engages the rearward cam 52, the slide 50 and its connected mechanism is again operated to lift the feeler 41 clear of the surface of the sheet between the jaws 29 and 30 and the engagement of the arm 37 with the stop 39 releases the cams 32 from the jaws 30 and permits the opening of the latter by the springs 31, so that the sheet drops upon the table 4.

So long as a sheet is properly fed and removed, for each impression, the operation of the machine continues as above described.

If, however, the gripper jaws 29 and 30 fail to pick up a printed sheet from the platen, the feeler 41 drops into the slot 42 in the jaw 30 as the arm 21 is retracted and the tail 45 of the feeler lever 40 is elevated by the spring 43 into the path of the rear flange 48 on the shaft 47. This prevents the turning of the shaft 47 and the descent of the slide 50 and trigger 52a when the roller 51 passes off the high point of the forward cam 52'. Consequently the trigger 52a engages and rocks the arm 54. The arm 54 acts through the parts 55, 57 and 58 to advance the elevated dog 59 and disengage the detent 60 from the pin 62a on the shaft 62. The shaft 62 is thereupon rotated by the spring 63 and turns the arm 62b into the path of the lug 65 on the segment 12, which is thereby held elevated and rendered inoperative to advance the feed rack. The turning of the shaft 62 also operates the yoke 62c carried thereby to close the valve 66 connecting the suction tube 68a with the chamber 67, thereby preventing the exhaustion of the feet 5' and the picking up of a further sheet from the feed table 3. The turning of the shaft 62 also operates the cam 62d on the end thereof to throw the link 69 which actuates the usual trip mechanism of the press and prevents contact of the bed and platen and the making of further impressions.

When the missed sheet has been removed from the platen manually by the attendant or by the jaws 29 and 30 on their next oscillation, the rod 64 is pushed in to rotate the shaft 62 against action of the spring 63. This

removes the arm 62b from its position in the path of the segment catch 65, disengages the yoke 62c from suction valve 66, and turns the cam 62d to release the press trip mechanism, 5 so that the press will again start feeding and printing.

If, however, the failure of the fingers 29 and 30 to remove a sheet from the platen results from a previous failure of the feet 10 5' to pick up a sheet from the table 3, the press and feed mechanism are not stopped by the rocking of the arm 54, because, as before described, the tooth 59 is not in a plane to engage the detent 60.

15 Having described my invention, I claim:

1. In apparatus of the character described, the combination with feed mechanism and delivery mechanism, of means for rendering said feed mechanism inoperative when said delivery mechanism is ineffective, and means for preventing the operation of said means last named when said feed mechanism fails to operate.

2. In apparatus of the character described, 25 the combination with feeding mechanism and delivery mechanism, of means operable by said delivery mechanism for controlling said feeding mechanism, and means operable by said feeding mechanism for controlling said means first named.

3. In apparatus of the character described, the combination of a sheet separator, means for moving a sheet from said separator to a press, delivery mechanism for removing a sheet from said press, and means operable by said delivery mechanism for controlling said sheet separator and moving means.

4. In apparatus of the character described, 40 the combination of feed mechanism, a segment for operating said feed mechanism, means for oscillating said segment, and means for rendering said last named means inoperative.

5. In apparatus of the character described, 45 the combination with sheet feeding means, of a segment for operating said sheet feeding means and comprising a cam having a peripheral runway and a by-pass runway connecting different sections of said peripheral runway.

6. In apparatus of the character described, the combination with feeding means, of a segment for operating said feeding means, 55 means for oscillating said segment and comprising a cam having a peripheral runway and a by-pass runway connecting different portions of said peripheral runway, and means for rendering said segment inoperative.

7. In apparatus of the character described, 60 the combination with a printing press, of feed mechanism comprising a reciprocable device, means for operating said device, and means for rendering said feed mechanism in-

operative during the continued operation of said machine.

8. In apparatus of the character described, the combination with a platen, of a sheet-feeding rack delivering to said platen, sheet separating mechanism for supplying sheets to said rack, sheet delivery mechanism for removing a sheet from said platen, and means operable by one of said mechanisms for checking the operation of said rack.

9. In apparatus of the character described, the combination of a feeder, an oscillatory member for reciprocating said feeder, means comprising a driving shaft for operating said oscillatory member, and means for latching said oscillatory member.

10. In apparatus of the character described, the combination of a feed rack, a toothed segment for operating said rack, means comprising a cam for operating said segment and means for latching said segment out of the path of said cam.

11. In apparatus of the character described, the combination with feeding mechanism, of means normally tending to check 90 the action of said feed mechanism, a device controlling said means last named, and means for operating said device.

12. In apparatus of the character described, the combination with feeding mechanism, means for operating said feeding mechanism, tensioned means for controlling said operating means, means for placing said tensioned means under tension, a device for holding said tensioned means under tension, 100 and means for tripping said device.

13. In apparatus of the character described, the combination of a trip sheet-separator, means for exhausting said separator, a valve for controlling said means, tensioned means tending to normally cut off suction from said separator, and means for controlling said tensioned means.

14. In apparatus of the character described, the combination of a sheet-separator, 110 a feeder, trip mechanism, and means for simultaneously rendering said sheet-separator and said feeder inoperative and for operating said trip mechanism.

15. In apparatus of the character described, the combination of a shaft, means normally tending to move said shaft in one direction, means for manually moving said shaft in the opposite direction, means for retaining said shaft in the position to which 120 it is moved by said manual means, and a sheet-separator, a feeder, and a trip mechanism controlled by said shaft.

In testimony whereof I have hereunto set my name this 16th day of June, 1925.

IRVING PHILLIPS.
